PROCESS AND APPARATUS FOR TREATING
HYDROCARBON FLUIDSMalcolm P. Youker, Bartlesville, Okla., assignor
to Phillips Petroleum Company, Bartlesville,
Okla., a corporation of Delaware

Application February 16, 1933, Serial No. 657,111

9 Claims. (Cl. 196—58)

This invention relates to improvements in a process for treating hydrocarbon fluids particularly to the cracking of heavy oils and the conversion of hydrocarbon gases to liquids and to an apparatus for accomplishing the aforesaid improvements.

In the cracking of heavy oils to gasoline or the like, or in the reverse process of converting hydrocarbon gases to liquid products, where tubular heaters are used to bring the raw materials to cracking or conversion conditions, unless the time of the reaction period is carefully controlled, over-cracking takes place and free carbon separates and either clogs the tubes or must be deposited in a suitable receptacle in the reaction zone to permit continuation of the process. In most cases it is undesirable to reach this carbon-forming condition and it therefore becomes necessary to cool the reaction products immediately after the proper time interval at conversion temperature has elapsed. My invention relates to a method of accomplishing this cooling whereby the formation and deposition of free carbon is inhibited and the cycle period for the process greatly lengthened.

In the apparatus whereby I accomplish the aforesaid improvements, I have introduced several novel features which will be described subsequently.

In the accompanying drawings used to illustrate my improved process and apparatus, Figure 1 is a diagrammatic representation of my process,

Fig. 2 is a section of my cooling apparatus, and Fig. 3 is a side view of the cooling apparatus.

Referring to the drawings, hydrocarbon material, either liquid or gas, is fed through line 1 by pump 2 to a heating coil 3 mounted in a furnace 4 in which is also mounted a burner 5 which supplies fuel for heating the hydrocarbon material in its passage through the coil 3, the combustion gases pass out of the furnace through the passage 6 and into the stack 7. A valve 8 in the burner line controls the heat input to the process. In the coil 3 the hydrocarbon material is raised to the required cracking or conversion conditions, the temperature, pressure and time of heating being so controlled that the optimum conditions will have been reached by the time the hydrocarbon material passes the back pressure valve 9 at the outlet of the coil 3, which is adapted to maintain any desired pressure in the coil 3. After passing valve 9, the highly heated material passes into a second coil 10, the members of which are generally of substantially the same cross-sectional area as those of the heating coil 3, although this is not

necessary and the tubes composing coil 10 may be larger or smaller than those composing coil 3 as the conditions of the process may dictate. Coil 10 is composed of horizontal layers of tubes. The tubes of one layer being directly above the tubes of the next lower layer, rather than in a "staggered" arrangement as is more common. This permits me to interpose vertically disposed continuous surfaces 11 between each pair of vertical rows of tubes and to each of these surfaces are fastened horizontally extending members 12 between each pair of horizontal layers of tubes. This arrangement causes the coil 10 to be divided into a number of vertical passages in each of which there is a single row of vertically disposed tubes and in which each tube is partially enclosed by the horizontally-extending members 12. The coil 10, together with the interposed surfaces, is mounted in a suitable housing 13 in the lower portion of which below the coil 10 are one or more breeched openings 14 in which are mounted dampers 15. Variable speed motors 16 drive fans 17 which force a current of cold air or other gas through the breeched openings 14. This current of air sweeps through the passages in the coil 10 formed by the surfaces 11 and 12 and cools the hydrocarbon material passing through the coil 10. The surfaces 11 and 12 are interposed for the purpose of permitting radiated heat to flow from the tubes forming the coil, to these surfaces and the heat then is carried away by the current of air. If the surfaces 11 and 12 were not interposed between the tubes, heat radiated by one tube would strike the tubes immediately surrounding it and would nullify the effect of the heat lost by the surrounding tubes, that is, one tube would simply heat those around it and the mutual exchange of radiated heat would prevent substantial cooling. By interposing the surfaces 11 and 12, this mutual interchange of heat is prevented and the heat impinging on these surfaces as a result of radiation from the tubes is swept from these surfaces by the current of air or gas.

The horizontally extending members 12 serve not only in this connection but also to restrict the openings through the passages so that greater velocities may be attained by the air or gas in its passage through the coil, more rapid heat transfer being thereby effected and the efficiency of the apparatus as a cooling device increased. Instead of supplying cooling gases by forced draft as by motors 16 and fans 17, the top of the housing 13 may be connected to the stack 7 by means of a suitable breeching not shown and cooling air

or gas drawn through the coil 10 by means of the natural draft of the stack.

The use of variable speed motors 16 and of dampers 15 permits wide variations in the quantity and velocity of the cooling gases. Dampers 15 may be so designed that they may be thermostatically controlled whereby the damper openings may be regulated by changes in temperature in the hydrocarbon material in coil 10, thus permitting continuous automatic control of the temperature of material leaving the coil 10. Such methods of control are known though I believe this particular application to be quite novel.

After leaving the coil 10, the hydrocarbon material cooled now to a temperature at which formation or deposition of free carbon is inhibited passes through a second back pressure valve 18. Because of the varying nature of the hydrocarbon materials treated, it may be desirable to maintain the coil 10 under the full pressure existing in coil 3 or it may be desirable to maintain coil 10 at a pressure reduced below that in coil 3 but above atmospheric, or it may be desirable to maintain coil 10 at atmospheric pressure. By the proper manipulation of valves 9 and 18, any of these pressure conditions may be imposed on the coils 3 and 10.

After passing through valve 18, the hydrocarbon material enters the separating chamber 19 where the vaporized material separates from the unvaporized material, and passes through line 20 to a fractionating system not shown. The unvaporized material passes out of the vaporizing chamber 19 through line 21 to other steps in the process, also not shown.

As one specific example of my process, I may heat a stream of gas oil in the coil 3 to a temperature of 900° F. under a pressure of 350 pounds per square inch, which pressure is maintained by the valve 9. After passing the valve 9 the highly heated material under a pressure reduced to 40 or 50 pounds passes through the coil 10 where it is subjected to the cooling action of a stream of cold air supplied by the blower 17 and the temperature of the material is thereby reduced to about 800° F. and on passing into the separating chamber 19 separates into vapors and liquid without substantial deposition of carbon at any point in the passage. On the other hand, if I did not interpose my cooling step, the highly heated material would, on entering the separating chamber 19, because of its high temperature continue to react and a substantial deposition of carbon would take place in the separating chamber 19 and cause a shut down for cleaning in a comparatively short time. By my process and apparatus, I am thus able to increase the cycle time from 4 to 5 days to 30 days or longer.

The conditions of temperature and pressure above described of course vary for the different stock treated.

It will be understood that I do not intend to be limited by any form or apparatus I may have described for the purpose of illustration but that I desire to claim all novelty within the scope of the appended claims.

What I claim and desire to secure by Letters Patent is:

1. In a process for treating hydrocarbon fluids, the improvements which comprise heating such a fluid in a first portion of a confined stream to suitable conversion conditions of time, temperature and pressure, reducing the pressure on the products of conversion in a second portion of the said confined stream, passing the second portion

of said stream back and forth between a series of partitions arranged in a cooling zone, radiating heat from the second portion of the stream toward said partitions, forcibly passing a cooling medium between said partitions and around the second portion of the stream, whereby said heat is dissipated and the second portion of the stream is cooled to check the conversion reaction, and separating the products of conversion. 5

2. In a process for treating hydrocarbon fluids, the improvements which comprise heating such a fluid in a first portion of a confined stream to suitable conversion conditions of time, temperature and pressure, reducing the pressure on the products of conversion in a second portion of the said confined stream, passing the second portion of said stream externally of the heating zone back and forth between a series of partitions arranged in a cooling zone, radiating heat from the second portion of the stream toward said partitions, forcibly passing a cooling medium between said partitions and around the second portion of the stream, whereby said heat is dissipated and the second portion of the stream is cooled to check the conversion reaction, and separating the products of conversion. 10 15

3. In a process for treating hydrocarbon fluids, the improvements which comprise heating such a fluid in a first portion of a confined stream to suitable conversion conditions of time, temperature and pressure, reducing the pressure on the products of conversion in a second portion of the said confined stream, passing the second portion of said stream back and forth between a series of partitions arranged in a cooling zone, radiating heat from the second portion of the stream toward said partitions, forcibly passing a gaseous cooling medium between said partitions and around the second portion of the stream, whereby said heat is dissipated and the second portion of the stream is cooled to check the conversion reaction, and separating the products of conversion. 20 25 30 35

4. In a process for treating hydrocarbon fluids, the improvements which comprise heating such a fluid in a first portion of a confined stream to suitable conversion conditions of time, temperature and pressure, partially reducing the pressure on the products of conversion in a second portion of the said confined stream, passing the second portion of said stream back and forth between a series of partitions arranged in a cooling zone, radiating heat from the second portion of the stream toward said partitions, forcibly passing a cooling medium between said partitions and around the second portion of the stream, whereby said heat is dissipated and the second portion of the stream is cooled to check the conversion reaction, then further reducing the pressure on the products of conversion, and separating the products of conversion in a separating zone. 40 45 50 55 60

5. An apparatus for treating hydrocarbon fluids comprising a furnace, a tubular heater arranged to be heated by the furnace and through which a hydrocarbon fluid may be passed in a confined stream, a cooling chamber, a tubular cooler in the cooling chamber and having its inlet connected to the outlet of the tubular heater, said tubular cooler consisting of connected tubes extending through the cooling chamber, continuous imperforate partitions in such chamber dividing said tubes into rows of tubes and segregating the rows from one another, said partitions forming passageways in which the rows of tubes are arranged, and means for forcing a cooling fluid 70 75 80 85 90 95 98

through said passageways and between the partitions and tubes for dissipating heat radiating from the tubes.

6. An apparatus for treating hydrocarbon fluids comprising a furnace, a tubular heater arranged to be heated by the furnace and through which a hydrocarbon fluid may be passed in a confined stream, a cooling chamber, a tubular cooler in the cooling chamber and having its inlet connected to the outlet of the tubular heater, said tubular cooler consisting of connected tubes extending through the cooling chamber, continuous imperforate partitions in such chamber dividing said tubes into rows of tubes and segregating the rows from one another, said partitions forming passageways in which the rows of tubes are arranged, and means for forcing a cooling fluid through said passageways and between the partitions and tubes for dissipating heat radiating from the tubes, the last mentioned means including a fan and a variable speed motor for driving the fan.

7. An apparatus for treating hydrocarbon fluids comprising a furnace, a tubular heater arranged to be heated by the furnace and through which a hydrocarbon fluid may be passed in a confined stream, a cooling chamber, a tubular cooler in the cooling chamber and having its inlet connected to the outlet of the tubular heater, said tubular cooler consisting of connected tubes extending through the cooling chamber, continuous imperforate partitions in such chamber dividing said tubes into rows of tubes and segregating the rows from one another, said partitions forming passageways in which the rows of tubes are arranged, means for forcing a cooling fluid through

said passageways and between the partitions and tubes for dissipating heat radiating from the tubes, and dampers for controlling the cooling fluid introduced into said passageways.

8. In a process for treating hydrocarbon fluids, the improvements which comprise heating such a fluid in a first portion of a confined stream to suitable conversion conditions of time, temperature and pressure, passing a second portion of said stream back and forth between a series of partitions arranged in a cooling zone, radiating heat from the second portion of the stream toward said partitions, forcibly passing a cooling medium between said partitions and around the second portion of the stream, whereby said heat is dissipated and the second portion of the stream is cooled to check the conversion reaction, and separating the products of conversion. 10 15

9. An apparatus of the character described, comprising a casing, a coil consisting of tubes extending through said casing, continuous imperforate partitions in the casing dividing said tubes into rows of tubes and forming radiating surfaces, said partitions forming substantially parallel passageways in which the rows of tubes are arranged, other partitions positioned between the first mentioned passageways and forming restricted throats, the ends of each passageway being open to permit parallel streams of a cooling fluid to flow in a single direction through the 20 25 30 passageways, and means for forcing a cooling fluid through the restricted throats at one end of said passageways, whereby the cooling fluid passes between the first mentioned partitions and past the tubes in each row. 35
